UNITED STATES PATENT OFFICE.

ALBERT W. McCASLIN, OF PITTSBURG, PENNSYLVANIA.

BLACKSMITH'S FORGE.

SPECIFICATION forming part of Letters Patent No. 781,843, dated February 7, 1905.

Application filed December 14, 1903. Serial No. 185,101.

To all whom it may concern:

Be it known that I, ALBERT W. McCASLIN, a resident of Pittsburgh, in the county of Allegheny and State of Pennsylvania, have invented a new and useful Improvement in Blacksmiths' Forges; and I do hereby declare the following to be a full, clear, and exact description thereof.

My invention relates to blacksmith or like forges.

One of the chief objects of my invention is to construct a forge in which provision is made for the storage of the coal and coke in convenient position for handling and without interfering with the movements of the blacksmith or his assistants about the forge.

To these ends my invention comprises the novel features hereinafter set forth and claimed.

To enable others skilled in the art to make and use my invention, I will describe the same more fully, referring to the accompanying drawings, in which—

Figure 1 is a side view in perspective of my improved forge. Fig. 2 is a front view in perspective of same. Fig. 3 is a side elevation, partly in section; and Fig. 4 is an enlarged detail in section of the hearth and receptacle below.

Like numerals indicate like parts in each.

In the drawings the numeral 2 designates a suitable floor or foundation upon which the forge is located. The forge illustrated is a double one, and as both sides are of the same construction a description of one will suffice.

Below the floor-level is the fuel-pit 3, said fuel-pit being preferably lined with the cast-metal box 4, said box having the inclined end and sides 5 and the cross-partition 6, dividing said box into two main compartments 7 and 8.

Erected over the box 4 is the hearth-frame 9, said hearth-frame being formed of cast-iron or, if desired, of wrought-iron or steel plates secured together. A cross-partition 9^a divides said hearth-frame, said partition and the side and end walls of said frame being provided with the lugs 10, depending from the lower edges thereof. The hearth-frame rests upon the upper edges of the box 4, and bolts 12 pass through the sides of said box

and the lugs 10 on said frame. In this manner the hearth construction is of a very durable form. Secured to the lugs 15 on the hearth-frame 9 is the plate 11, which forms the receptacle 15^a. 55

The hearth 16 is supported within the hearth-frame, said hearth resting upon the plates 17 and the plate 18. The plates 17 are inclined, as shown in Fig. 4, said plates being supported upon the lugs 19 on the end wall 60 and partition 9^a of the hearth-frame, while the plate 18 is supported upon the lugs 20 of the hearth-frame. In this manner the hearth is suspended within the hearth-frame, the inclined plates 17 making access to the compartment 7 through the opening 21 in the side of the hearth-frame very convenient for the introduction and removal of coal from said receptacle. The clay which forms the hearth 16 is supported upon the plates 17 and 18, 70 and embedded in said clay is the twyer 22, by means of which the blast is furnished to the hearth. This twyer is connected up with the blast-pipe 23, valves 24 being provided for regulating the supply of air to said twyer. 75 The hearth 16 is formed with a hollow or depression, as indicated in Fig. 4, and within this hollow is placed the coal and coke for burning, said coal or coke being adapted to come up to the level of the hearth-frame and 80 forming a smooth bed for working.

An ash-chute 25 is secured to one side of the hearth-frame, the inlet to said ash-chute being slightly above the hearth-level, so that the ashes on said hearth may be readily discharged 85 into said chute, and the outlet of said chute opens into the ash-holder 26, which is formed within the box 4 by the partition 27. If desired, however, this ash-chute may extend outwardly, as indicated in dotted lines in Fig. 90 4, so as to discharge into the receptacle 28. A pipe 29 discharges into the receptacle 28, said pipe leading from the twyer 22, and said pipe is provided with the cap 30. This pipe 29 is employed for cleaning the twyer 22 of 95 ashes or other material which may collect therein and discharging the same into the receptacle 28.

The receptacle 8 below the floor-level may be divided by the removable partition 31, 100

which fits in guideways 31^a in said box 4. This receptacle 8 provides for the reception of different kinds of coke.

Located above the hearths is the double hood 33, which may be of any suitable construction and supported in any suitable manner.

When my improved forge is in operation, the fine coal or slack is introduced into the 10 receptacle 7 and a proper quantity of water applied thereto for bringing it to the proper condition for use. This water may be supplied from the tank 36. The coke is introduced into the receptacle 8, and where more than 15 one kind of coke is used the partition 31 is employed. The hearth having been properly supplied with the coal and coke for the fire, the fire is then lighted and the blast turned on.

As fresh coal is needed from time to time it may 20 be readily obtained by introducing a shovel through the opening 21 in the side of the hearth-frame, and in view of the inclined sides of the box the removal of the coal is accomplished without difficulty, while the slanting 25 bottom of the hearth formed by the plates 17 enlarges the capacity of said box or receptacle. In this way the coal is always within easy reach of the operator, while at the same time the boxes, keys, or other cumbersome utensils 30 usually employed in blacksmith-shops to contain the necessary supply of coal and coke, as well as the ashes, are dispensed with and there is nothing to interfere with the operations of the blacksmith or his assistants about

35 the forge. In the handling of large work it often requires several men about the forge, and where coal-boxes and other receptacles are about the forge the movements of the workmen are interfered with. At the same 40 time the coke is in position to be easily reached, the slanting bottom 5 of the coal-receptacle enabling it to be withdrawn without difficulty. In case the coal has not been properly consumed when the fire is put out 45 in the forge the said coal may be raked into the box 15^a and used again upon the forge being lighted up. The ashes may be drawn off through the chute 25 and deposited into the receptacle 26, where they are out of the way 50 and from which they may be readily removed.

By the use of the receptacles below the floor-level and beneath the hearth the coke and coal are out of sight, and a neat clean appearance is given to the forge and its surroundings, 55 while there is no opportunity for the waste of materials.

What I claim is—

1. In a blacksmith or like forge, the combination with the shop-floor having a fuel-pit formed therein, of a box-like frame located over said fuel-pit, converging side plates supported by said frame, a hearth carried by said plates, said frame having an opening leading to said fuel-pit, and said fuel-pit having a sloping wall extending down thereto. 60

2. In a blacksmith or like forge, the combination with the shop-floor having a fuel-pit formed therein, of a box-like frame located over said fuel-pit, converging side plates supported by said frame, a hearth carried by said plates, said frame having an opening leading to said fuel-pit, and said fuel-pit having a sloping wall extending from a point beyond said frame down into said pit. 70

3. In a blacksmith or like forge, the combination with the floor having a pit formed therein, a partition dividing said pit into independent fuel and ash receptacles, a frame located over said pit having an opening leading to said fuel-receptacle, a hearth supported by said frame, and a chute leading from said hearth to said ash-receptacle. 75

4. In a blacksmith or like forge, a box-like frame, lugs on said frame, inwardly-sloping side pieces resting on said lugs, a bottom piece 80 resting on said side pieces, a hearth supported by said side and bottom pieces, said box-like frame having a fuel-storage space below said hearth and an opening leading thereto for the removal of the coal. 90

5. In a blacksmith or like forge, a floor or foundation having a depression formed therein, a hearth-frame over said depression, a box in said depression divided by a partition into compartments, and openings in the side and end of said hearth-frame leading into said box. 95

6. In a blacksmith or like forge, a floor or foundation having a depression formed therein, a hearth-frame over said depression divided by a partition into compartments, said 100 hearth-frame having an opening in the side thereof leading into one of said compartments, and said box extending beyond the front end of said hearth-frame and having a sloping outer end. 105

In testimony whereof I, the said ALBERT W. McCASLIN, have hereunto set my hand.

ALBERT W. McCASLIN.
